(57) **CLAIM**

The ornamental design for a cam lock, as shown and described.

DESCRIPTION

FIG. 1 is an isometric view of the cam lock showing my new design in use with a box having a detachable lid with the cam lock shown in an unlocked position;

FIG. 2 is an isometric view of the cam lock showing my new design in use with a box having a detachable lid with the cam lock shown in the locked position holding the lid onto the box; FIG. 3 is a right-front isometric view of the cam lock shown in an unlocked position in isolation as seen in FIG. 1;

FIG. 4 a top view of thereof;

FIG. 5 is left-side view thereof;

FIG. 6 is a rear view thereof;

FIG. 7 is a bottom view thereof;

FIG. 8 is a front view thereof

FIG. 9 is an inverted right-side view thereof;

FIG. 10 is a right-front isometric view of the cam lock shown in the locked position in isolation as seen in FIG. 2;

FIG. 11 is a front view thereof;

FIG. 12 is a left-hand side view thereof;

FIG. 13 is a rear view thereof;

FIG. 14 is a right-hand side view thereof;

FIG. 15 is a front view thereof; and,

FIG. 16 is bottom view thereof.
